BARBECUE GRATE

Filed Oct. 19, 1929

UNITED STATES PATENT OFFICE

CHARLES B. POLHEMUS, OF SAN JOSE, CALIFORNIA

BARBECUE GRATE

Application filed October 19, 1929. Serial No. 400,831.

It is the object of the present invention to provide a barbecue grate so mounted as to be readily transported without disturbing its operative relationship to the fire bed used in conjunction therewith.

It is another object of the invention to provide a device of the character indicated wherein a warming table may be operated in conjunction with the grate as an integral part of the general assembly.

It is still another object of the invention to provide a device of the character indicated wherein a grate and spit are operative as a unit relative to the fire bed but independently operative for their separate purposes.

Finally, it is an object of the invention to provide a device of the character above indicated that will be economical to manufacture, simple in form and construction, strong, durable, and highly efficient in its practical application.

The drawing is a perspective illustration of a device embodying my invention, parts broken away.

In the embodiment of the invention herein disclosed, I show at 1 a fire-box mounted on wheels as 2 and legs 3 and fitted with a handle 4, the box being lined with fire-brick except at the forward end 6 which consists merely of a single sheet metal plate as shown. The forward end of the box extends a distance beyond plate 6 as indicated at 7 and is provided with a sloping bottom 8a and a flat top 8, this end portion being entirely enclosed to form a closed chamber 9.

At 10—10 are a pair of standards mounted on opposite ends of the box 1 and connected by a top bar as 11. At opposite ends of bar 11 are mounted pulleys as 12 over

which cables 13 operate, the cables supporting a grate 14 as shown. The cables are connected at 15 to a hand lever 16 pivotally mounted as at 17 to an arm 18 on box 1.

In the standard 10 adjacent the lever 16 are formed a number of notches at 19 to receive the said lever and hold the same in any given position.

On two opposite corners of the grate 14 are mounted depending ears 20—20 to form

When a fire is built in the fire-box the air is heated in the chamber 9 and since this is a closed chamber the top 8 is quickly heated and maintained in a heated condition even when the fire is reduced to coals.

By manipulating the handle 16 the grate may be raised or lowered as desired to bring the grate into the desired position relative to the fire, being gradually lowered as the fire dies down so that the heat from the fire may be used most efficiently.

By combining the grate and spit as disclosed either one may be used independently of the other or they may both be used at the same time.

The device may be readily wheeled from place to place, and the construction of the fire-box is such that the fire and heat therefrom is confined within desired limits, permitting use of the device indoors if so desired.

It is to be understood, of course, that while I have herein shown and described but one specific embodiment of the invention, changes in form, construction, and method of assembly and operation may be made within the scope of the appended claim.

I claim:

A device of the character described comprising, a vehicle having an open topped fire-box mounted thereon, and having a permanently closed chamber formed thereon separated from the fire-box by a heat conducting partition, a heating plate forming the top of the chamber, and a grate mounted for vertical adjustment over the top of the fire-box.

CHARLES B. POLHEMUS.
